CLAIM

I claim the ornamental design for a diagnostic wrist band, as shown and described.

DESCRIPTION

FIG. 1 is a perspective view of a diagnostic wrist band showing my new design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof; and,

FIG. 8 is a perspective view of the diagnostic wrist band shown in an environment of use.

The broken-line showing of the arm in FIG. 8 illustrates environment and forms no part of the claimed design. All other broken lines, including stitching, illustrate portions of the diagnostic wrist band that form no part of the claimed design.
